(57) CLAIM

The ornamental design for a travel pillow, as shown and described.

DESCRIPTION

FIG. 1 is a back-perspective view of the invention;

FIG. 2 is a front perspective view thereof;

FIG. 3 is a right and left-side view thereof;

FIG. 4 is a back-view thereof;

FIG. 5 is a front view thereof;

FIG. 6 is a bottom view thereof;

FIG. 7 is a top-perspective view thereof;

FIG. 8 is a back-perspective view of the invention in an open configuration; and,

FIG. 9 is a front-perspective view of the invention in an open configuration.

The broken lines in the drawings depict portions of the travel pillow that form no part of the claimed design.
